UNITED STATES PATENT OFFICE.

JACOB HYSON MOORE, OF DELAVAN, KANSAS.

VERTICALLY-ADJUSTABLE HINGE.

1,103,607.

Specification of Letters Patent. Patented July 14, 1914.

Application filed August 14, 1913. Serial No. 784,725.

To all whom it may concern:

Be it known that I, JACOB H. MOORE, a citizen of the United States, residing at Delavan, in the county of Morris and State 5 of Kansas, have invented new and useful Improvements in Vertically-Adjustable Hinges, of which the following is a specification.

This invention has relation to hinges and 10 it consists in the novel features hereinafter described and claimed.

An object of the invention is to provide a hinge the leaves of which may be adjusted with relation to each other in order that a 15 door which is supported by the hinge may be raised or lowered at an edge portion in order that the door may fit snugly in its frame. It frequently happens that after doors are hung they sag at one or the other 20 of their edges so that they bind in the frame. By use of the present hinge should such sagging or binding occur the leaves of the hinge may be shifted in order that the door may fit snugly in the frame or clear the 25 floor or other surface when swung over the same.

In the accompanying drawing: Figure 1 is a side elevation of one form of the hinge with parts broken away and parts in section. 30 Fig. 2 is a similar view of another form of the hinge.

As shown in Fig. 1 the hinge comprises a leaf 1 having at its ends and at one edge knuckles 2. The other leaf 3 has 35 at one edge and at a point between its ends a knuckle 4. Pins or pintles 5 are screw threaded through the knuckles 2 and are provided at their outer ends with slots 6. The inner ends of the pins 5 are 40 reduced in diameter as at 7 as they enter the knuckle 4. Washers 8 are mounted upon the pins 5 at the outer ends of the reduced portions 7 and are seated upon shoulders 9 formed at the inner ends of the threaded 45 portions of the said pins 5. These washers 8 bear against the ends of the knuckle 4. When the hinge is applied to a door and in the event that the door should sag a screw driver may be inserted in the slots 6 of the pins 5 and the said pins may be rotated whereby they are moved longitudinally in the knuckles 2. The knuckles 2 are spaced from each other for a distance greater than the length of the knuckle 4 and consequently

as the pins 5 are moved longitudinally as 55 above indicated the washers 8 bearing against the ends of the knuckle 4 will cause the leaf 1 to move with relation to the leaf 3. Inasmuch as the leaf 3 is attached to the frame and the leaf 1 to the door or vice versa 60 the door is moved with relation to the frame and consequently the door may be positioned to fit snugly in the frame.

In the form of hinge as shown in Fig. 2 the same general arrangement of the parts 65 is observed the exception being that the form of hinge as shown in the said figure is of a heavier type than that shown in Fig. 1 and the leaves 1 and 3 are provided with additional knuckles in the intermediate 70 members of which is located an additional pin 10.

Having described the invention what is claimed is:

1. A hinge comprising two leaves each 75 having knuckles, the knuckles upon one leaf being spaced apart for a distance greater than the length of the knuckle on the other leaf, pins screw-threaded in the knuckles of the first mentioned leaf and having diametrically reduced cylindrical end portions 80 the knuckle of the second mentioned leaf having a longitudinal bore which extends from end to end thereof and which receives the reduced cylindrical ends of the pins. 85

2. A hinge comprising two leaves having 90 knuckles, the distance between the knuckles upon one leaf being greater than the length of the knuckle upon the other leaf, pins screw threaded in the knuckles of the first mentioned leaf and having diametrically reduced cylindrical end portions and provided at the ends of said reduced portions with shoulders, washers located on the said shoulders and bearing against the ends of 95 the knuckle of the second mentioned leaf, the knuckle of the second mentioned leaf having a longitudinal bore which extends from end to end thereof and which receives the reduced cylindrical ends of the pins. 100

3. A hinge comprising two leaves each 105 having knuckles, the distance between the knuckles upon one leaf being greater than the length of the knuckle upon the other leaf, pins screw threaded in the knuckles of the first mentioned leaf and having diametrically reduced cylindrical end portions, the knuckle of the second mentioned leaf having

a bore which receives the reduced cylindrical ends of the said pins and a third pin carried in said bore and interposed between the reduced ends of the first mentioned pins 5 and adapted to prevent the first mentioned pin from binding against the knuckle of the second mentioned leaf.

In testimony whereof I hereunto affix my signature in the presence of two witnesses.

JACOB HYSON MOORE.
